UNITED STATES PATENT OFFICE.

HENRY G. SELLMAN, OF DETROIT, MICHIGAN.

APPARATUS FOR BUILDING CONCRETE STRUCTURES.

Application filed January 29, 1920. Serial No. 354,833.

To all whom it may concern:

Be it known that I, HENRY G. SELLMAN, a citizen of the United States of America, residing at Detroit, in the county of Wayne 5 and State of Michigan, have invented certain new and useful Improvements in Apparatus for Building Concrete Structures, of which the following is a specification, reference being had therein to the accompanying drawings.

This invention relates to an apparatus for the progressive erection of symmetrical structures and its object is to so construct and arrange such an apparatus as to greatly 15 facilitate the work by making the apparatus readily adjustable to the work in hand and for the progressive raising of the apparatus during the building operation. A further object is to provide such an apparatus with 20 an adjustable scaffold and with means for the delivery and distribution of building material, and with suitable means for suspending and raising wall mold sections. It is also an object to provide certain other new 25 and useful features in the construction, arrangement and combination of parts, all as hereinafter more fully described.

With the above and other ends in view, the invention consists in the matters herein- 30 after set forth and more particularly pointed out in the appended claims, reference being had to the accompanying drawings in which—

Figure 1 is a transverse vertical section 35 through an apparatus embodying the invention and illustrating its application in use;

Fig. 2 is a plan view of the same;

Fig. 3 is a perspective view of a dis- 40 tributing hopper;

Fig. 4 is a detail view of a rotatable guide ring showing parts in section to more clearly disclose the construction;

Fig. 5 is a detail view of a supporting 45 sleeve showing the same applied to a mask and in transverse vertical section;

Fig. 6 is a detail view of an upper sup- 50 porting sleeve upon a mast and illustrating the manner of raising and applying additional sections to the mast;

Fig. 7 is a perspective detail of an ex- 55 tendsible supporting arm; and

Fig. 8 is a side elevation of the apparatus illustrating its application for use in build- 55 ing other than cement structures.

In Figs. 1 and 2 of the drawings the ap-

paratus is illustrated as applied to the building of cement or concrete structures of circular form, but it will be understood that the same may be used wherever applicable in 60 the building of structures from other materials such as brick or of structures having other symmetrical forms, and while a specific construction of apparatus and detailed construction and arrangement of parts has 65 been shown, it will be understood that the same is merely illustrative of the invention and is susceptible of changes which are contemplated as falling within the scope of the 70 appended claims.

To build a wall, such as the circular wall of a silo, grain elevator, or stack, from cement, concrete, or the like, it is necessary to provide forms or molds into which the concrete is dumped and as the wall thus formed 75 becomes self-sustaining, to remove the lower mold sections therefrom and place them above the mold sections recently filled, thus progressively building up the wall by alternating the molds. It therefore becomes 80 necessary to provide suitable means for supporting these expanding outer and contracting inner mold sections in place and raising the same from time to time as the work progresses. Further, it is desirable to provide 85 a suitable platform or scaffold for the workmen which may be readily raised in a like manner and that such scaffold be carried and supported by the same supporting and raising means which is employed in manipulating the molds in order to cheapen the apparatus and facilitate the work. In order to further facilitate the work of building concrete structures, it is desirable that means 90 be provided for the ready distribution of material and that such means be arranged to operate in conjunction with the supporting means to the end that it be guided and directed in such distribution and the whole 95 comprise a complete operative apparatus 100 for carrying out the several steps and for facilitating the work of building structures of this character.

In Figs. 1 and 2 suitable sectional telescoping molds are illustrated comprising sheet metal walls 1 which are properly curved to together form between them a circular concrete wall, said wall sections being strengthened by channel and angle bars 2 and 3 secured along their upper and lower 110 and side edges respectively, but it will be understood that any suitable mold construc-

tion may be employed, said mold forming no part of the present invention. In building a structure of considerable height, such as a silo, grain elevator, stack or other similar structure, these molds are placed in superposed relation and in vertical alignment to form, in a progressive manner, a continuous wall of the desired height and these molds may have a form which will produce an upwardly tapering wall, if found desirable. Any suitable means, such as rods 4 may be provided to engage openings in the flanges of the channel bars 2 for detachably holding the mold sections in vertical alignment, and any suitable means (not shown) may be provided for detachably holding together the abutting ends of the several sections comprising each mold.

The apparatus embodying the invention comprises a sectional hollow mast indicated as a whole at 5 and consisting of a plurality of sections, one end 6 of each of which is reduced in diameter and externally screw-threaded to engage the internally screw-threaded end of an adjacent section, thus providing an externally smooth continuous hollow mast which may be set up at the axis of the structure to be built and as the work progresses, additional sections may be added to increase the height of the mast beyond the top of the wall being built. Free to slide upon this mast is a pair of sleeves 7 and 8 which sleeves are spaced apart and held in spaced relation by tie rods 9 engaging openings in flanges 10 and 11 on the sleeves near their adjacent ends and rigidly held by jamb nuts on the screw-threaded ends of the rods. The mast sections are each provided with a series of transverse holes 12 to receive bolts or pins 13, one being inserted through the mast beneath the lower end of each sleeve to prevent the sleeves from sliding down on the mast. Each bolt 13 is provided with a nut at each end or a head at one end and a nut at the other to hold the bolt in place and permit of its ready removal, each nut or nut and head being in the form of a hook 14 as shown in Fig. 5 to provide a ready place of attachment for suitable tackle (not shown) blocks of which may be attached to hooks adjacent the lower end of the upper sleeve 8 and the other blocks attached in any convenient manner to the lower sleeve, so that by means of this tackle the connected sleeves and apparatus supported thereby, may be raised, sliding upon the mast, and the bolts then engaged with other holes higher up on the mast to securely hold the sleeves in adjusted position.

Each supporting sleeve is also formed with a wide annular flange 15 intermediate its ends and with a parallel flange 16 of lesser width spaced a short distance from and above the flange 15, and each of these flanges is formed with a rib at its outer edge

the rib 17 on the flanges 15 extending upwardly and the rib 18 on the flange 16 extending downwardly to form bearing surfaces on said flanges 15 to engage the ends of supporting arms 19 and 20 placed between them and extending radially outward from the sleeves. These arms are preferably channel iron bars placed with their channels opening upwardly, the arms 19 being of such a length that they will extend outwardly to near the inner mold wall 1 within the mold and form supports for a scaffold which is made of a plurality of formed sections 21 each having hooks 22 at each end to engage over the flanges of the channel arms and hold the scaffold sections in place. A circular platform or scaffold is thus supported by the mast within the upper mold and carried by the sleeve 7 to be raised or lowered therewith. To brace and strengthen the arms 19, brace rods 23 having turn-buckles 24 are detachably attached at one end to said arms by forming hooks on the ends of the rods to engage pins 25 extending across the channels of the arms, and the hooks of the opposite or upper ends of the rods are engaged with suitable ears 26 secured to the flange 11 on the sleeve 8 by means of the tie-rods 9 passing therethrough.

The supporting arms 20 are preferably of greater length than the arms 19 so that they will extend outwardly over and at a considerable distance above the upper end of the wall being formed to provide supports for other purposes hereinafter described, there being one or more of these arms according to the purpose for which they are to be used, and these arms are braced and carried by rods 60 having turnbuckles 27, the lower ends of said rods being attached to the arms in the same manner in which the rods 23 are detachably connected to the arms 19, and the upper ends of said rods 60 being formed with hooks to detachably engage over an edge flange of a collar 28 on the mast, which collar is spaced from and rigidly held at a considerable distance above the upper end of the upper sleeve 8 by tie rods 29 secured at one end to the collar and at their opposite ends to the flange 61 on the sleeve 8.

The arms 19 or 20 may be made extensible as shown in Fig. 7, if found desirable by making each arm of two channel members, one to telescope within the channel of the other and adjustably securing the two parts together in any suitable manner as by a clamp 30 and a bolt 31 carried by the outer member and passing through slots in the inner member. The arms may thus be lengthened or shortened according to the diameter of the structure which is being built.

When the apparatus is employed in the building of concrete structures as shown in Figs. 1 and 2, one of the arms 20 may be employed as a support for suitable hoisting

mechanism, such as blocks and tackle indicated at 32 for hoisting a suitable bucket 33 or other carrying receptacle for concrete, or as shown in Fig. 8, a suitable number of these arms may be employed to form suitable supports from which scaffolding 34 may be suspended in any suitable manner, as by bars 35 having loops 36 at their upper ends to receive the ends of the arms, thus providing an interior scaffold 21 and an exterior scaffold 34, to facilitate building a circular brick wall having any desired height and thickness.

In the building of concrete or other walls, the bucket 33 is preferably hung in a bail 37 to swing thereon and the side of the bucket is provided with a hook 38 to engage a bail 39 upon a hopper 40 which is positioned upon the top of the mold walls 1 to travel thereon, said hopper being set within a suitable rectangular frame 41 which is provided with rollers 42 one at each end, said rollers being of a length to rest upon the upper channel bars 2 of the mold and travel thereon. The bucket is also provided with a hinged bottom 43 made of two parts pivotally connected at 44 to the side edges of the bottom of the hopper. The bottom 43 is normally held in closed position by means of a lever 45 pivoted to the ends of the hopper and connected intermediate its ends by links 46 with the hinged portions of the bottom. The two levers 45 at opposite ends of the hopper are connected by a cross-bar 47 and upon the ends of the hopper are lugs or catches 48 to engage beneath the levers 45 and hold the bottom in closed position.

The bucket 33 is drawn up by means of the tackle 32 and as it comes opposite the hopper, the hook 38 engages the bail 39 and further upward movement of the bucket will cause it to be tilted and dump automatically into the hopper. After it has been so dumped it is lowered and then the hopper may be moved manually along the top of the mold to the position where it is desired to dump the concrete. The operator then disengages the levers 45 from the hooks or lugs 48 and permits the contents of the hopper to be discharged directly into the mold, the lower end of the hopper preferably extending downward into the top of the mold a short distance.

To prevent accidental disengagement of the hopper carrier from its track or upper end of the mold, and to guide it in its travel around this circular track, an arm or shaft 49 is rigidly secured to the carrier frame 41 transversely thereof and extends inwardly therefrom.

A second guide rod or arm 50 is attached to the inner end of the arm 49 by means of a suitable slip joint connection indicated at 51 comprising two plates bolted together and formed with bearing sockets for the two arms

49 and 50 which extend at an angle to each other. The arms may thus be adjusted relatively within the connection 51 by loosening the bolts connecting the two plates and sliding either rod endwise through its socket therein, and then tightening the bolts to clamp the rods firmly between the plates. The rod 50 is rigidly attached in any suitable manner at its upper end to a ring 52 which is free to rotate within a channel-shaped guide ring 53, suitable anti-friction rollers 54 being interposed between the ring and guide so that the ring will turn freely. The channel shaped guide 53 is secured to the upper sleeve 8 concentrically thereof by means of arms 55 secured to the flange 11 on the sleeve and to the inner side of the guide 53. The carrying frame 41 for the hopper 40 is thus connected by the rigid adjustable arms 49 and 50 with the ring 52 so that the frame is held at a fixed distance from the axis of the mast and as the hopper is pushed along the top of the mold, it is guided in its circular path about the axis of the mast by this rigid connection but is not impeded in its travel because of the manner in which the ring 52 to which it is connected is mounted.

By this construction the weight of the apparatus is carried by the sleeves 7, 8, which are free to slide upon the hollow mast 5 and the entire structure may thus be readily raised or lowered at any time by means of suitable tackle and adjusted upon the mast by removing the pins 13 and placing them in other openings provided therefor in the mast, said pins also affording a place of attachment for the tackle to the mast. The radial arms 19 are carried by and readily detachable from the sleeve 7 and afford a rigid support for the scaffold 21 upon which the workmen may stand and which forms a suitable platform for carrying material.

In raising or lowering the apparatus, the scaffold structure moves therewith but by reason of the knock-down construction, it may be quickly removed or detached at any time.

In a like manner the upper sleeve 8 forms a suitable support for the arms 20 which are securely and detachably connected thereto in the same manner in which the arms 19 are carried by the sleeve 7. These arms 20 are thus carried by and movable with the apparatus as it is raised or lowered and form suitable spars for the support of hoisting apparatus, scaffolding or other devices.

To facilitate the raising of additional mast sections and attaching them to the upper end of the mast 5 as the work progresses, a suitable spar 56, shown in Fig. 6 of the drawing is provided. This spar is provided with a pin 57 at its lower end to engage in an opening in the flange 61 on the upper sleeve 8 and is also provided with a

hook 58 to engage over the collar 28 which is carried by the tie rods 29. By raising the apparatus so that the sleeve 8 will be adjacent the upper end of the upper section of the mast, the collar 28 will be raised to a position considerably above the upper end of the mast and will thus support the spar 56 in such a position with its upper end far above the upper end of the mast so that by 10 attaching suitable tackle, indicated at 59 to the upper end of the spar, the mast section may be hoisted to position with its lower end above the collar and then lowered into the collar and said end screwed into the 15 upper end of the upper section of the mast.

An apparatus is thus provided which is simple in construction and readily available for adjustment for building tall structures and it is also so constructed as to be adaptable for use in building structures of various sizes and from any desired material, it being adaptable for use in manipulating the molds for a concrete wall as well as forming a rigid support for all of several devices necessary 20 in building structures of this character. The apparatus is also so constructed that it may be very readily taken apart for transport from place to place and may be quickly set up for use, the mast being formed of detachable sections of convenient length to provide the main support for the apparatus which may be increased in length as the work progresses to provide a mast of sufficient length for supporting the apparatus 25 for building a structure of any desired height.

Obviously, changes may be made in the construction and arrangement of parts, size, proportion or form thereof within the scope 40 of the appended claims, without departing from the spirit of the invention and I do not therefore limit myself to the particular construction shown.

Having thus fully described my invention, 45 what I claim is:—

1. In an apparatus of the character described, the combination of a supporting mast, a member sleeved upon the mast to slide freely thereon, means for holding the 50 member in adjusted position upon the mast, upper and lower parallel annular flanges upon said member, said lower flange being of greater width than the upper flange and adapted to engage beneath and form a support for radial arms, said upper flange being adapted to engage over the ends of said arms, and radial arms loosely engaged at 55 one end between said flanges and extending radially from the mast.

2. In an apparatus of the character described, the combination of a vertical supporting mast, carrying means sleeved upon the mast to slide thereon, means engaging the mast for holding said carrying means 60 in adjusted position upon the mast, two sep-

arate series of radially extending arms, and means adjacent the upper and lower ends of said carrying means for loosely engaging said arms, said means comprising outwardly extending parallel annular flanges, the lower 70 flange of each pair being of greater width than the upper flange to form a support for said arms at a distance from their ends and said upper flange engaging the upper sides of said arms near their ends, the weight of 75 the projecting outer portions of said arms serving to hold the arms engaged with said flanges.

3. In an apparatus of the character described, the combination of a vertical supporting mast, a pair of sleeves slidable upon the mast and held in spaced relation, two series of radially extending arms, spaced parallel radially extending flanges on each of the sleeves between which the inner ends 80 of said arms are loosely engaged, a series of rods detachably connected to the arms intermediate their ends at one end and formed with hooks at their opposite end to detachably connect said ends to said sleeves, and means carried by the mast for holding the sleeves in adjusted position upon the mast. 85

4. In an apparatus of the character described, the combination of a supporting mast, a hopper adapted to be mounted upon the top of parallel mold walls to travel thereon as a double track with the discharge end of the hopper between said walls, and rigid means rotatable about the mast and connected to said hopper and mast for guiding said hopper in its travel upon the upper end of said mold walls. 90

5. In an apparatus of the character described, the combination of a supporting mast, a scaffold carried by said mast, a hopper adapted to be supported upon the top of parallel mold walls to travel thereon as tracks with the discharge end of the hopper between the walls, and guiding means connected to the hopper at one end and to the mast at its opposite end to rotate thereon. 105

6. In an apparatus of the character described, the combination of a supporting mast, a hopper, a carrying frame for supporting the hopper above the space between said walls, a pair of rollers on the frame for spanning the space and running upon the upper ends of mold walls, a circular guide carried by the mast, a ring rotatable in the guide and rigid connecting means between the ring and the hopper carrying frame to guide the same in its travel. 110

7. In an apparatus of the character described, the combination of a hopper, a carrying frame supporting the hopper over the space between mold walls, rollers on the frame adapted to engage the top of the mold walls and span the space therebetween, a hinged bottom for the hopper to discharge 115 directly into the space between the mold 120 walls. 125

walls, means on the hopper for opening and closing the hinged bottom, a supporting mast adapted to be positioned concentrically with mold walls, guiding means connecting 5 the hopper and mast and rotatable about the axis of the mast an arm rotatable about the mast and extending outwardly therefrom over the mold walls, a bucket carried by said arm, and means on said bucket for en- 10 gaging said hopper.

8. In an apparatus of the character described, the combination of a hopper frame adapted to engage and travel upon the top of circular mold walls, a hopper carried by 15 said frame with its lower end adapted to extend into the space between mold walls,

a hinged bottom for said hopper, means for opening and closing said bottom, a bail carried by the hopper, a supporting mast, guiding means rotatable upon the mast and 20 rigidly connected to said hopper frame, supporting means carried by the mast and extending radially therefrom over the hopper, and a pivotally supported bucket carried by said supporting means and having a hook 25 to engage the bail and hopper.

In testimony whereof I affix my signature in the presence of two witnesses.
